UNITED STATES PATENT OFFICE

158,060

CRADLE FOR A TELEPHONE HANDSET

Isadore Flatter and Mimi Carmel,
Wembley Park, EnglandApplication April 1, 1949, Serial No. 1,768
In Great Britain August 31, 1948

Term of patent 14 years

(Cl. D26—14)

To all whom it may concern:

Be it known that we, Isadore Flatter, formerly of Russian nationality, but now stateless, and Mimi Carmel, of British nationality, and both residing at 62 Alexandra Court, Empire Way, Wembley Park, Middlesex, England, have invented a new, original, and ornamental Design for a Cradle for a Telephone Handset, of which the following is a specification, reference being had to the accompanying drawings, forming part thereof.

We claim:

The ornamental design for a cradle for a telephone handset, as shown.

ISADORE FLATTER.
MIMI CARMEL.
